RICHARD MONTGOMERY, OF NEW YORK, N. Y.

Letters Patent No. 86,028, dated January 19, 1869.

IMPROVED METALLIC COLUMN.

The Schedule referred to in these Letters Patent and making part of the same.

To all whom it may concern:

Be it known that I, RICHARD MONTGOMERY, of the city, county, and State of New York, have invented a new and improved Corrugated-Metal Column; and I do hereby declare the following to be a full and exact description thereof, reference being had to the accompanying drawings, forming a part of this specification, in which—

Figure 1 is an elevation, illustrating two of my improved columns, supporting and connected by a horizontal transverse beam;

Figure 2, a view, in perspective, of one of my columns, fig. 1, constructed to afford bearings for four horizontal beams extending therefrom in opposite directions; and

Figure 3 is a transverse section in the line $x x$ of fig. 1.

Similar letters indicate like parts in all of the figures.

The nature of my invention consists in uniting and combining four of my patent doubly-corrugated metal beams or plates so as to form a neat, compact, strong column for the support of all manner of structures.

The column is constructed as follows:

Two of my doubly-corrugated and flanged plates or beams A A are placed slightly apart, face to face, with their central folds inward.

Two additional plates or beams A' A', of the same

form and size, are then placed with their flanges c c against the outer faces of the outer folds of the beams A A, so as to cover and embrace within their folds the flanges d d of the said beams A A.

The four plates thus longitudinally interlocked are united and secured together by means of bolts e e extending between the flanges c c of the two plates A A', transversely through the folds of the plates A A, and secured by nuts, as shown in fig. 3; or they may be secured together by rivets or other suitable fastenings known in the art.

The columns thus made may be inserted and secured within suitable cast-iron bases B B, and the upper ends of one or more of the four plates of the column may be bent or curved to a horizontal plane, to afford a bearing for horizontal beams, as may be required. (See fig. 2 of the drawings.)

Having thus fully described my invention, I claim as new, and desire to secure by Letters Patent—

A corrugated-metal column or support, constructed substantially as herein set forth.

R. MONTGOMERY.
